UNITED STATES PATENT OFFICE.

FREDERIK SÖRENSEN, OF COPENHAGEN, DENMARK.

UMBRELLA.

SPECIFICATION forming part of Letters Patent No. 783,325, dated February 21, 1905.

Application filed March 30, 1904. Serial No. 200,752.

To all whom it may concern:

Be it known that I, FREDERIK SÖRENSEN, manufacturer, a subject of the King of Denmark, residing at Amagertorv 10, Copenhagen, in the Kingdom of Denmark, have invented new and useful Improvements in Umbrellas and Sunshades, of which the following is a specification.

My invention relates to an umbrella or sunshade, the essential feature of which is that in the closed-up condition of the umbrella the runner is either wholly or partly received by a chamber formed in or on the end of the handle or around the stick.

My invention is illustrated in the accompanying drawings, in which—

Figure 1 shows the handle portion of a closed umbrella, partly in vertical section; and Fig. 2, an elevation of the same seen at right angles to Fig. 1.

a is the stick.

b represents the stretchers, pivoted to the runner *c* in well-known manner, and *d* is the handle to which the stick is secured.

e is a spring-catch retaining the runner and the ends of the stretchers within the chamber *f*, so that the ends of the stretchers are carried within the chamber when the umbrella is in a closed position in order to protect the ends of the stretchers and to prevent the tearing of garments thereby.

In the handle *d* there is formed a chamber or recess *f*, which in the umbrella shown in the drawings is constituted by boring out the end of the handle. This chamber *f* receives the runner *c* when the umbrella is closed. Instead of the arrangement shown the chamber can, if desired, be formed by a sleeve or barrel fitted to the handle, so as to form an extension thereof.

The spring-catch *e* to admit of its being readily depressed may be provided with a button or pin *g*, and the runner may be fur-

nished with a knob *h* or the like thumb-piece for the purpose of enabling it to be the easier 45 run up and down the stick. In cases where the chamber *f* is formed by boring out the handle the walls of the chamber may be strengthened by a metal sleeve being slid over the handle end. 50

By means of the above-described arrangement the umbrella or sunshade in closed condition presents a particularly thin and neat appearance, the runner lying snug and compact within its chamber in or at the handle 55 end. Another advantage is that the fabric of the umbrella-cover is protected from wear through frictional contact with the runner.

Having thus described my invention, what I claim as new, and desire to secure by Letters 60 Patent, is—

In an umbrella, the combination with a stick furnished with a chamber having a wall provided with a slot and a perforation, of a slotted runner provided with a lateral thumb-piece 65 constructed to extend through the slot in said wall, said runner sliding into said chamber, stretchers connected to said slotted runner, the ends of said stretchers being carried into said chamber, a spring-catch secured to the 70 stick and extending through the slotted runner into the chamber and retaining the runner and ends of the stretchers within the chamber when the umbrella is in a closed position, and means passing through the perforation in the 75 wall of said chamber for operating said spring-catch to release the runner, substantially as described.

In witness whereof I have hereunto signed my name, this 12th day of March, 1904, in the 80 presence of two subscribing witnesses.

FREDERIK SÖRENSEN.
